(57) **CLAIM**

The ornamental design for a handle body for surgical device, as shown and described.

DESCRIPTION

FIG. 1 is a front, top and left side perspective view of a handle body for surgical device, showing my new design; FIG. 2 is a front, bottom and right side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a cross-sectional view thereof, taken along the line 9-9 in FIG. 5; and,

FIG. 10 is an enlarged cross section view thereof, taken along the line 10-10 in FIG. 3.

The evenly spaced broken lines and dot-dash broken lines immediately adjacent the shaded areas represent the bounds of the claimed design while all other broken lines are directed to environment and are for illustrative purposes only; the broken lines form no part of the claimed design. The dot-dot-dash lines in the cross-section FIGS. 3 and 5 views are used to identify the cross-section views and are for reference purposes only.
